UNITED STATES PATENT OFFICE.

HARRY SOREF, OF MILWAUKEE, WISCONSIN, ASSIGNOR TO MASTER LOCK COMPANY, OF MILWAUKEE, WISCONSIN, A CORPORATION OF WISCONSIN.

MASTER KEY.

Application filed April 17, 1922. Serial No. 554,159.

The invention relates to an improved construction of master key, whereby it is better adapted to the more efficient performance of its functions.

5 The invention resides in a master key in which the end of the solid shank of the key is flush with the tumbler catch. The new construction endows the key with a greater amplitude of movement in feeling for the 10 tumblers, and thus its range of serviceability is increased over the older forms of master keys, in which the shank has uniformly been provided with a projection extending beyond on the face of the tumbler catch, 15 such projection in its engagement with the parts of the lock casing acting to limit the movement of the key, and preventing the proper positioning of the tumblers.

But in my improvement, the objections of 20 the older constructions are overcome, and the new form of key is rendered available for effective operation under all conditions.

25 The novel features residing in the invention will be pointed out in the appended claims.

The drawing which accompanies this specification, shows in perspective view a key embodying my invention.

Referring to the drawing, it will be noted 30 that the forward end of the shank 10 of the key terminates at 11 in the plane of the front face of the tumbler catch 12. The omission of the usual projection extending forwardly of the shank and beyond the front face of 35 the tumbler catch 12, removes an obstruction which, in the older form of keys, acted as an interference in many cases with the successful operation of the key in opening the lock when the key thereto had become 40 lost. The said projection pivoted in the far side of the lock and often constituted an interference by reason of its engagement with the lock casing. It restricted the amplitude of movement of the key so that the latter was

rendered ineffective, and necessitated the resort to other devices to effect the opening of a closed lock.

But with the use of my invention, the former objections are caused to disappear, and a single key with its much wider range 45 of movement is enabled to effect an operation which has heretofore been possible only after protracted effort requiring the trial, in many instances, of numerous keys to achieve the immediate results flowing from the use of 50 my invention.

The drawing illustrates the preferred specific and most usual form in which the invention is embodied, in that the free or outer edge of the tumbler catch 12 is provided with opposite, narrow projections 55 13 and 14, extending axially with respect to the shank 10 of the key, and slightly forward of the front face of the tumbler catch 12, and also slightly rearward of the rear face 60 of the said catch.

Having thus described my invention, what I claim and desire to secure by Letters Patent of the United States, is:

1. A master key provided with a solid 70 shank and fixed tumbler catch, the whole of which latter is adapted to be entered in the lock casing, and the end of the shank being flush with the front face of the tumbler catch.

2. A master key provided with a solid shank and a fixed tumbler catch, the whole of which latter is adapted to be entered in the lock casing, and the end of the shank being flush with the front face of the tumbler catch, the free edge of the tumbler catch being provided with opposite, narrow projections extending axially with respect to the 75 said shank.

In testimony whereof, I have signed my 80 name at Milwaukee, this 15th day of April, 1922.

HARRY SOREF.
